CLAIM

The ornamental design for a sports night switch, as shown and described.

DESCRIPTION

FIG. 1 is a perspective view of a sports night switch showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the embodiment of the invention shown in FIG. 1; and,

FIG. 9 is a perspective view of another embodiment of the invention shown in FIG. 1.

The broken lines indicate unclaimed portions of the design and form no part of the claimed design.

1 Claim, 6 Drawing Sheets(56)
